(74) Attorney, Agent, or Firm — Thomas A. Runk;
Brooks Kushman P.C.(57) **CLAIM**

We claim the ornamental design for a photo booth, as shown and described.

DESCRIPTION

FIG. 1 is a top, right side, and front perspective view of a photo booth configured in accordance with the present invention;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate unclaimed portions of the photo booth, and form no part of the claimed design.
